US00D569425S

(12) **United States Design Patent** (10) **Patent No.:** **US D569,425 S**
Law et al. (45) **Date of Patent:** **** May 20, 2008**

(54) **ASYMMETRICAL DATA DEVICE WITH INDENTATION**

(75) Inventors: **Christopher Law**, Pelham Manor, NY (US); **Vlad Guzner**, Brooklyn, NY (US); **Maorung Lin**, Brooklyn, NY (US); **David Sohn**, Fort Lee, NJ (US)

(73) Assignee: **Visa U.S.A. Inc.**, San Francisco, CA (US)

(**) Term: **14 Years**

(21) Appl. No.: **29/269,954**

(22) Filed: **Dec. 11, 2006**

(51) **LOC (8) CL. 19-08**

(52) **U.S. CL. D19/10; D14/436**

(58) **Field of Classification Search** D19/1-25, D19/34.1-34.5, 35-42, 52; D3/207, 208, D3/212, 215; D20/22, 24, 27, 28, 40-43; 40/1.5, 6, 27, 107, 119, 120, 124, 299, 358, 40/617, 634, 636, 60, 662; 281/15.1, 33, 281/38; 108/60, 61; 248/44.1, 316.5, 460; 229/74; 206/39.6; D11/79; D8/347; D14/356, D14/434-438

(57) **CLAIM**

The ornamental design for an asymmetrical data device with indentation, as shown and described herein.

DESCRIPTION

FIG. 1 is a perspective view of the asymmetrical data device with indentation showing my new design;

FIG. 2 is a top plan view thereof;

FIG. 3 is a left side elevation view thereof;

FIG. 4 is a right side elevation view thereof;

FIG. 5 is a bottom plan view thereof;

FIG. 6 is a front elevation view thereof; and,

FIG. 7 is a rear elevation view thereof.
